(57) **CLAIM**

The ornamental design for a container and valve assembly, as shown and described.

DESCRIPTION

FIG. 1 is a top perspective view of a first embodiment of a container and valve assembly showing our new design; FIG. 2 is a top plan view of the assembly of FIG. 1; FIG. 3 is a front and back side view of the assembly of FIG. 1;

FIG. 4 is a left and right side view of the assembly of FIG. 1; and,

FIG. 5 is a bottom plan view of the assembly of FIG. 1. The broken lines shown in the drawing figures are for illustrative purposes only and form no part of the claimed design.
